(57) **CLAIM**

The ornamental design for a digital ear and head thermometer, as shown and described.

DESCRIPTION

FIG. 1 is a front side perspective view of the digital ear and head thermometer, showing the design;

FIG. 2 is a top view of the digital ear and head thermometer with end cap removed, showing the design;

FIG. 3 is a second front side perspective view of the digital ear and head thermometer, showing the design;

FIG. 4 is a bottom view of the digital ear and head thermometer, showing the design;

FIG. 5 is a top view of the digital ear and head thermometer, showing the design;

FIG. 6 is a right side inverted view of the digital ear and head thermometer, showing the design;

FIG. 7 is a left side inverted view of the digital ear and head thermometer, showing the design;

FIG. 8 is a back view of the digital ear and head thermometer, showing the design; and,

FIG. 9 is a front view of the digital ear and head thermometer, showing the design.
